(57) **CLAIM**

The ornamental design for teleplier as shown and described.

DESCRIPTION

1. Teleplier
  2. Teleplier
  3. Teleplier
  - 1.1 : Front axonometric view of the first embodiment
  - 1.2 : Front
  - 1.3 : Right side view
  - 1.4 : Rear view
  - 1.5 : Left side view
  - 1.6 : Top
  - 1.7 : Bottom
  - 1.8 : Enlarged axonometric view of a part
  - 2.1 : Front axonometric view of the second embodiment
  - 2.2 : Front
  - 2.3 : Right side view
  - 2.4 : Rear view
  - 2.5 : Left side view
  - 2.6 : Top
  - 2.7 : Bottom
  - 2.8 : Enlarged axonometric view of a part
  - 3.1 : Front axonometric view of the third embodiment
  - 3.2 : Front
  - 3.3 : Right side view
  - 3.4 : Rear view
  - 3.5 : Left side view
  - 3.6 : Top
  - 3.7 : Bottom
  - 3.8 : Enlarged axonometric view of a part
- Fig. 1.1-1.7 are seven views of a first embodiment of a teleplier; Fig. 2.1-2.7 are seven views of a second embodiment of the teleplier; Fig. 3.1-3.7 are seven views of a third embodiment of the teleplier; Each of Fig. 1.8, 2.8 and 3.8 is enlarged view of a part, in particular a hand-grip, of a respective embodiment of the teleplier; the design is applied

(Continued)

to the hand-grip of the teleplier; The broken lines in the drawings illustrate portions of the teleplier that form no part of the claimed design.

1 Claim, 24 Drawing Sheets
